UNITED STATES PATENT OFFICE

LADISLAUS DOBOS, OF BINGHAMTON, NEW YORK

HEADLIGHT FOR AUTOMOBILES

Application filed February 26, 1929. Serial No. 342,770.

The object of my invention is to provide a form of head light for automobiles or motor vehicle headlights, and to provide in connection with the headlight of usual construction a simple and highly efficient device, to concentrate the light rays in a small area immediately forward of the vehicle on which the headlight is mounted, and to eliminate as far as possible glare; also to provide a hood for the headlight so positioned as to cover more or less of the upper part of the light and thus screen the more blinding rays and form a shade for the headlight, and also to provide a reflector designed to direct the light rays from a lamp downward on the road surface.

With these objects in view my invention consists of the following novel features of construction and arrangement of parts as more clearly appear in the accompanying drawing, and as pointed out in the claim; reference being had to the accompanying drawing, in which:

Fig. 1 is a side view of my device.

Fig. 2 is a front view of my device.

Fig. 3 is a front view of a modified form of my device.

Fig. 4 is a side view of a modified form of my device.

Fig. 5 is a side view of a fragmentary part of a modified form of my device.

The same reference characters denote like parts in each of the several figures of the drawing.

In carrying out my invention, I provide a body portion A, in somewhat bell shape formation, extending from the inner end towards the outer end, the lighting bulb Y being mounted in the inner end; the outwardly expanding part is divided on a central horizontal line 5 into upper and lower parts and the upper portion forming a hinged lid B, in expanding outline and hinged to the body A, by the hinge 2. The upper portion is projected at the front into a sloping projection, as shown in Fig. 1. From the upper alignment of the body A, horizontally, I have an elongated hood C, which extends in somewhat pointed outline to its outer end 3.

As a further part of the device, I have vertically mounted above the lower front of

the body A, lens 4 directly under the hood C. The lens 4 may be a magnifying lens, to divide the rays of light. When for any reason I desire to reach the bulb Y for replacement, or any other purpose, I can open 55 the lid B, hinged at 2, and tip it back.

In a further modified form of my device, I have the body A, having the hood B, and the hood hinged at 2 at the side of the body A, as shown in Fig. 3, and when for any 60 reason it is desired to open the hood B, it may assume the form or position as shown in Fig. 3.

In a further modified form of my device, as shown in Figs. 4 and 5, I have a body A, 65 as shown in Fig. 4, and mounted on the body A, I have the body C, as shown in Fig. 4 and Fig. 5. The body C having the sloping front, and the shade formation. The part C, as shown in Fig. 5, may be formed separately from the body A, and may be joined to the body as shown in Fig. 4, in any convenient manner, either by hooks or by screw thread connection, and when so used the parts C and A assume the relation and position, as shown in Fig. 4. On the body C I have mounted the hooks 6, 6, adapted to hook over the lugs 7, 7 on the body A. 75

In the construction of my device, I have the sloping outer front 3, as shown in Figs. 80 1, 2, 4 and 5, and projected vertically above this sloping outer end I have mounted the lens 4. It is understood that the lower or inner side of C is to have a reflector surface and that the inner surface of the sloping end 85 3 is also to have a reflector surface; the rays of light extending from the bulb Y contact with the reflector surface on the inner side of the sloping front 3, are then projected upward to the interior surface of the hood 90 C, thence outward and downward towards the ground surface directed by the conformation of the hood C.

Having thus described my invention what I claim as new and for which I desire Letters Patent is as follows:

A headlight for automobiles, comprising a flaring casing having a body portion open at its top, a complementary lid portion hingedly connected at the rear to the body por- 100

tion at a right angle to the vertical axial plane of the headlight and forming with the body portion a complete headlight casing, an integral anti-glare hood portion shaped to conform to the headlight casing, projecting forwardly from the lid and extending in front of the body portion, and a reflector on the under surface of the projecting hood.

5 In testimony whereof I have affixed my
10 signature.

LADISLAUS DOBOS.
